FLOYD C. FURLOW, OF MONTCLAIR, NEW JERSEY, ASSIGNOR TO OTIS ELEVATOR COMPANY, OF JERSEY CITY, NEW JERSEY, A CORPORATION OF NEW JERSEY.

SYSTEM OF CONTROL FOR ELECTRIC ELEVATORS.

1,268,111.

Specification of Letters Patent.

Patented June 4, 1918.

Application filed November 5, 1915. Serial No. 59,738.

To all whom it may concern:

Be it known that I, FLOYD C. FURLOW, a citizen of the United States, residing in Montclair, in the county of Essex and State of New Jersey, have invented a new and useful Improvement in Systems of Control for Electric Elevators, of which the following is a specification.

My invention relates to elevators, and 10 more particularly to an improved system of control for electrically operated elevators.

The invention more essentially consists in the provision of means, automatically to control an elevator car in stopping to effect an exact landing, the elements involved in accomplishing this result being operable independently of the car speed and load, and being in the form of auxiliary apparatus, operable independently of the main motor 15 and controlling means.

As is well known, considerable skill and accuracy is necessitated on the part of an elevator operator, in order to stop the elevator car exactly at a floor landing. This 20 is so particularly on account of the tendency of the elevator car to coast or overrun a landing, even after the motive power is cut off and the brake applied. Thus for varying car loads and speeds it becomes 25 most difficult to effect an exact car landing, it being the case in many instances for the elevator car to either overrun or underrun the landing, in which event the operator then resorts to what is commonly termed 30 an "inching operation" to bring the car exactly level with the landing. This operation is objectionable for the reasons that it disrupts the car schedule and is wasteful of power. Thus it is the aim of the 35 present invention to overcome the above objectionable features, in a most practical and simple manner as illustrated in the accompanying drawings, in which Figure 1 illustrates in general arrangement the more 40 essential elements of a car switch controlled electrical elevator system, in accordance with the present invention; Fig. 2 is a somewhat enlarged elevational view of a certain portion of Fig. 1, taken on the line 45 a—a in direction of the arrows b—b, certain parts being broken away; Fig. 3 is a side view of Fig. 2 with certain parts in section.

The apparatus consists of an elevator car

C, operated through any well known system of roping and hoisting mechanism by electric motor M. I have illustrated simply for example, a drum H, around which the car hoisting rope may pass or to which it may be connected, the drum being operable by the motor M through a usual worm and gear connection G. The electric motor M may be of either a direct or alternating current type, the latter type being illustrated herein, it receiving current from an alternating current source of supply, designated D, D', D''. A brake pulley P is rotatable with the main motor shaft 1.

The direction of rotation of the motor M is controlled by means of electro-magnetic reversing switches R, R', whose operating windings are controlled from the elevator car by a usual car switch S.

The parts thus far described form the more essential elements of a typical elevator system with well known functions, and are thus described only in general.

Coming now to the elements which form more particularly the subject matter of the present invention, they will be described in detail.

A reversible auxiliary motor X is adapted to rotate a worm 2, in mesh with a worm wheel 3. The worm wheel 3 is carried loosely on the main motor shaft 1. A brake apparatus B is rotatable bodily with the worm wheel 3, and about the brake pulley P. Arms 4 connect the brake apparatus to the worm wheel. The brake apparatus may be of any well known type in which the brake shoes 5 are released electrically, as by means of an electromagnet 6, and applied mechanically, as by means of the usual brake springs 7.

The auxiliary motor as before stated is reversible, the circuits controlling the same being controlled by a pair of electrical switches 8 and 9 pivotally mounted on the elevator car. These switches in turn are controlled independently by means of cams 10 and 11, fixed in the elevator hatchway at the floor landing. Although only one floor landing, and one set of cams thereat, is illustrated herein, it will be understood that there may be any number of floors, with a duplicate set of cams at each floor. Thus in order to avoid unnecessary duplication and in view of the fact that a dupli-

cate operation is effected at each floor landing by the action of the cams, it is thought sufficient in order for a clear understanding of the invention, to illustrate only one floor and one set of cams.

The cams 10 and 11 are positioned in the elevator hatchway in different vertical planes, the switch 8 coacting with the cam 10 automatically to control the auxiliary motor in a manner to operate the car downwardly, and the switch 9 coacting with the cam 11, automatically to control the auxiliary motor in a manner to operate the car upwardly.

15 Auxiliary back contacts 12, 12' on the reversing switches act in conjunction with the switches 8 and 9 to control the auxiliary motor circuits.

20 The various elements through a complete cycle of operation will now be described.

With the car switch S in center position, the car and its operating elements are at rest, with the brake shoes applied to the brake pulley P by the springs 7.

25 Assume now it is desired to cause the elevator car to descend, say from an upper floor, down to the floor at which the car is shown.

For the operation we will assume the car 30 switch is operated toward the left hand, bringing the segment 14 into electrical engagement with the fixed contact 15. A circuit is now completed for the operating winding of the reversing switch R', causing the same to close, and thereby direct current to the motor M and brake magnet 6. The brake magnet will now operate to release the brake shoes from the brake pulley P, and the motor will now rotate in a direction to cause the elevator car to descend.

40 As the car approaches the desired landing it is stopped, by the operator centering the car switch S, thus disconnecting the motor and brake from the source of power supply.

45 The brake shoes will now be applied to the pulley P, bringing the car to rest. Assume now for example, that the descending car is heavily loaded, and that after the car switch is centered, the car tends to coast

50 past or overrun the landing. Now in order to meet this contingency, the auxiliary motor is brought into operation automatically to actuate the elevator car to effect an exact landing, the operation being as follows.

55 The car having overrun the landing, brings the roller 9' associated with the switch 9 into engagement with the cam 11, thus closing the switch. This switch 9 now being closed directs current to the auxiliary mo-

60 tor X and the phases or leads being traced by way of wires D and 16 to back contacts 12, of reversing switch R, wire 17 to back contacts 12 of reversing switch R', wire 18, contacts 19, and thence to the terminal by way of wire 20; wire 21 is a common return

wire connecting to the common lead wire D'; and the other lead or phase wire being traced from the lead wire D', wire 21, back contacts 12'; wire 22, contacts 19' and thence by wire 23 to the other stator terminal. The auxiliary motor X receiving current will now effect rotation of the main motor shaft 1 through the connections comprising the worm 2, worm wheel 3, and the brake apparatus B, whose shoes are now applied to the brake pulley P. The brake apparatus B now rotating bodily with the brake shoes applied to the pulley, in this instance now serves as a form of clutch mechanism or connector between the auxiliary motor X and the elevator car. In this manner, the shaft 1 is caused to rotate and through the worm and gear connection G, effects an upward movement of the elevator car at an approximately slow speed. Now the instant the car becomes exactly level with the floor landing, the roller 9' rides off the cam 11, thus permitting the switch 9 to open, and in this manner cause the auxiliary motor to be stopped. It will be pointed out, that the worm 2 and worm wheel 3 are in practice, designed so as to form practically a lock between the auxiliary motor and rotatable brake apparatus, so that with all the parts at rest, the brake apparatus will, in view of the lock formed by the worm 2 and worm wheel 3, act positively to hold the elevator car at rest.

Now in case the operator centers the car switch, to cause the descending car to stop some distance above the landing, the roller 8' will in this event, engage the cam 10 to close the switch 8. The switch 8 being closed directs current to the auxiliary motor to effect an operation thereof in a reverse direction to that just described, thereby causing the elevator car to descend at an approximately slow speed. The instant the car comes level with the floor landing, the supply of current to the auxiliary motor is cut off, by reason of the roller 8' riding off the cam 10. In this manner the elevator car is stopped exactly level with the floor landing.

115 In operating the elevator car in an ascending direction of travel, the parts operate in substantially the same manner as heretofore described in connection with the descending direction of travel. In this instance, however, the reversing switch R closes, and directs current to the main motor M to cause it to rotate in a reverse direction to that just described, thereby causing the car to ascend.

120 However, the auxiliary apparatus for automatically controlling the elevator car to effect an exact landing operates as just described, in the event of the car overrunning or underrunning a landing, either in ascending or descending.

It will be noted that since the circuits for the auxiliary motor include the back contacts on the reversing switches R and R', a simultaneous operation between the main and auxiliary motors is effectively prevented; or in other words, the auxiliary motor is operable automatically only in the event of the car switch being centered, with the elevator car bearing such relation to the landing as to bring the switches 8 and 9 thereon into engagement with a respective cam 10 or 11.

In an application, Serial Number 59,736, filed November 5, 1915, I have described and shown a hydraulic elevator, with electric means to control the same, to level the car with a landing; but I do not claim in the application Serial Number 59,738, a hydraulic elevator.

It will be understood that the invention is equally applicable to a direct current elevator system as well as to an alternating current system as herein shown, and to an automatic push button controlled elevator, as well as a car switch controlled elevator.

One skilled in the art may make obvious changes in the details and arrangement of parts without departing from the spirit and scope of my invention, and I wish therefore not to be limited to the precise arrangement and details as are herein illustrated and described.

What I claim as new and desire to secure by Letters Patent of the United States is:—

1. In an electric elevator, the combination of the car, an electric hoisting motor, and electric means to control the motor, automatically controllable by the movement of the car, to cause the motor to operate to bring the car to a level with a desired landing whether the car over-runs or under-runs the said landing.

2. In an electric elevator, the combination of the car, an electric hoisting motor mechanism, a controller therefor, comprising switches, on the car, in the circuit of the motor mechanism, and cams on the hatchway to close the switch on the car, as and when the car approaches a desired landing, and release the switch to open position, upon the car becoming level with the said landing.

3. In an electric elevator, the combination of the car, an electric main hoisting motor and an auxiliary electric hoisting motor to operate the car, an automatically operable electric means, controllable by the movement of the car, and operable by the movement of the car whether the car over-runs or under-runs a desired landing, automatically to control the operation of the auxiliary motor to level the car with the landing.

4. In an elevator, the combination of the car, an electric hoisting motor mechanism, electric means to control the hoisting motor mechanism, automatically operable by the movement of the car, at a landing, to cause

the hoisting motor mechanism to operate to maintain in effect the car level with the landing, in loading and unloading.

5. In an elevator, the combination of the car, an electric hoisting motor mechanism, an operating circuit for the motor mechanism, electric means, comprising switches on the car, operable to close the circuit, and cams on the hatchway, to engage the switches, to close them, operable by the movement of the car, at the landing, to close the switches or release them to open position, to cause the motor mechanism to maintain in effect the car level with the landing, in loading and unloading.

6. In an elevator, the combination of the car, a hoisting motor mechanism, an electric operating circuit for the hoisting motor mechanism, switches in the circuit, carried on the car, cams on the hatchway, at a floor landing, to engage and close the switches by the movement of the car, to close the circuit to the hoisting mechanism, and to release the switches to open the said circuit, the cams and switches being positioned relatively to each other close enough together so that, upon the movement of the car from a position of rest level with the landing in loading or unloading, the cams will thereupon engage the switches and close them, to cause the hoisting motor mechanism to maintain in effect the car level with the landing.

7. In an elevator, the combination of a car, main and auxiliary electric hoisting motors, a car switch for controlling the main motor, and means controllable by centering the car switch to the off position, to enable the auxiliary motor to be operated to level the car automatically with a landing whether the car over-runs or under-runs the landing.

8. In an elevator, the combination of a main electric hoisting motor, a controlling mechanism therefor, an auxiliary electric hoisting motor, an operating circuit therefor, a controlling mechanism for the auxiliary motor including a switch and means controllable by the controlling mechanism for the main motor, to cause the operating circuit for the auxiliary motor to close, automatically to level the car with a landing whether the car over-runs or under-runs the landing when the main motor is not in operation in hoisting.

9. In an elevator, the combination of an electric hoisting motor mechanism, comprising main and auxiliary motors, supply circuits therefor, a car, and a car switch and reversing switches, the latter carrying back contacts, in the supply circuit for the auxiliary motor, the back contacts being closed when the car switch is in an open position, switches in the circuit for the auxiliary motor, cams to engage and

close the latter switches and subsequently to release them to open position, by the movement of the car.

10. In an electric elevator, the combination of the car, an electric hoisting motor mechanism, controlling switches for the motor mechanism, a cam to close one of the switches by the movement of the car as and when it approaches a landing, to have the 10 motor mechanism continue in hoisting operation in order to move the car to the landing, and substantially when the car is level with the landing, to release the switch, to open position, to allow the motor mechanism 15 to cease its hoisting operation, and an additional cam to close another one of the switches by the movement of the car, in case the car over-run the landing, and effect a movement of the car in a reverse direction, 20 to bring the car back to the landing over-run and thereupon, release the switch to have the car so brought back stop level with the landing.

11. In an electric elevator, the combination with the car, an electric hoisting motor mechanism, a switch to control the motor mechanism, additional controlling switches

for the motor mechanism, a cam to close one of the additional controlling switches by movement of the car as it approaches a landing, and thereby cause the motor mechanism to continue its hoisting operation to move the car toward the landing, and when the car is level with the landing, to release the switch to an open position and allow the 35 car to stop, an additional cam operable by the car, if and when the car in its movement shall coast past the landing, to close one of the said switches, and effect a movement of the car in a reverse direction, and 40 bring the car back to the landing over-run and thereupon release the switch to stop the car at the landing, and means to prevent the said additional controlling switches from functioning while the car is under the 45 control of the switch first named above.

In testimony whereof, I have signed my name to this specification in the presence of two subscribing witnesses.

FLOYD C. FURLOW.
